PACKED FIRE-CRACKER

Hatsutaro Yamagishi, Taishocho, Taihokushi,
Taiwan, Japan

Application August 19, 1935, Serial No. 36,930

1 Claim. (Cl. 102—22)

The present invention relates to an improvement in fire cracker packages.

An object of the invention is to provide such a package of a simple character, of cheap material and easy to manufacture.

A further object of the invention is to provide a package which permits easy inspection of the contents while being waterproof, and exposes the fuses outside of the package even while the package is closed.

Further objects will appear from the following description and drawing in which,

Fig. 1 is a plan view showing the package in fully unfolded condition,

Fig. 2 is a similar view showing the side flaps folded over the fire crackers,

Fig. 3 is a similar view showing the package completely closed, and

Fig. 4 is an elevational side view of the completed package.

The wrapper 3 is of suitable waterproof transparent or semitransparent paper and is of the crosslike form shown consisting of a central portion, end portions 7 and 8, and side portions 6 and 5, 5', each of which forms a continuation of the central portion. One of the side portions, 5, 5' in the drawing, is divided into two substantially equal parts 5 and 5' by a notch 4 preferably perpendicular to its outer edge. The purpose of this notch will appear later.

A preferably rectangular area 9 in the middle part of the central portion is covered with paste.

Two rows of fire-crackers are secured to the wrapper by this paste, all of them lying parallel and with their fuse ends inward and the fuse ends of corresponding crackers in the two rows separated by a space substantially equal to or a

little greater than the width of the notch 4. The fire-crackers in each row are separated from each other by a slight space so that one unit may be detached without disturbing the others. The fuses are laid parallel to each other and to the sides of the notch 4 in the space between the fuse ends of the two rows of fire-crackers but extend beyond the confines of the wrapper when it is closed as shown in Figs. 2, 3 and 4.

At the free end of one of the end portions 8 in the drawing, a strip 10 is covered with paste and when the side portions 6 and 5, 5' are folded over the fire-crackers and the end portions 7 and 8 are folded together thereover, the paste covered strip 10 serves to hold the wrapper in closed condition.

What I claim is:

A package comprising a wrapper of substantially transparent paper, having a substantially rectangular body portion, end extensions and side extensions from the edges thereof, paste covering a limited area of said body portion, and a paste covering a strip at the extremity of one of the end extensions, two rows of fire crackers laid parallel each to each, and held in position by the paste on said body portion, with the fuse ends of one row spaced from the fuse ends of the other row there being a space between the individual crackers of each row, a notch in one of the side extensions registering with the space between the fuse ends of the crackers and the fuses laid parallel to each other and extending through said notch, the side extensions being folded over said crackers and the end extensions folded over the side extensions and held by the paste strip.

HATSUTARO YAMAGISHI.
